UNITED STATES PATENT OFFICE.

HARRY E. GUYER, OF PHILADELPHIA, PENNSYLVANIA.

DESIGN FOR AN EYEGLASS-CASE.

SPECIFICATION forming part of Design No. 30,045, dated January 24, 1899.

Application filed December 31, 1898. Serial No. 700,863. Term of patent 7 years.

To all whom it may concern:

Be it known that I, HARRY E. GUYER, a citizen of the United States, residing in the city and county of Philadelphia, State of Pennsylvania, have invented and produced a new and useful Design for an Eyeglass-Case, of which the following is a specification, reference being had to the accompanying drawings, forming part thereof.

5 The leading feature of my design for an eyeglass-case is a case having an open top, closed ends, and a hump on one side thereof.

10 Figure 1 represents a perspective view of an eyeglass-case embodying my design. Fig. 2 represents a section thereof on line xx , Fig. 1.

In the drawings, A designates an eyeglass-case composed of the sides B and C, the open top D, the closed bottom E, and the closed ends F. On the side B is the hump G.

Having thus described my invention, what I claim as new, and desire to secure by Letters Patent, is—

The design for an eyeglass-case substantially as shown and described.

HARRY E. GUYER.
